UNITED STATES PATENT OFFICE

2,499,792

FARM MACHINE FOR LOADING AND
UNLOADING GRAIN

Ellis E. Starr, Ridgeville, Ind.

Application November 13, 1947, Serial No. 785,719

3 Claims. (Cl. 214—83.18)

1

This invention appertains to novel and useful improvements in vehicles adapted to be driven and actuated by a suitable prime mover.

An object of this invention is to transport, retain and distribute grain in an improved manner.

Another purpose of this invention is to provide improved means for carrying out the above mentioned function.

Another purpose of this invention is to provide an improved means for controllably actuating an endless conveyor in a hopper, provided in a vehicle.

Another purpose of this invention is to provide improved means for urging the grain from the hopper to and through an outlet port.

Another object of this invention is to provide an improved and simplified device of the character described which may be completely actuated and controlled from the rear portion thereof.

Another object of this invention is to provide a simplified device of the character described which lends itself well to commercial manufacture.

Ancillary objects and features of novelty will become apparent to those skilled in the art, in following the description of the preferred form of the present invention, illustrated in the accompanying drawings, wherein:

Figure 1 is a pictorial elevational view of the preferred form of the invention, showing the same utilized in association with a tractor.

Figure 2 is an enlarged elevational view illustrating a detail of construction, particularly the clutch mechanism used in the present invention and forming a portion thereof;

Figure 3 is an enlarged plan view of the vehicle forming the major portion of the present invention;

Figure 4 is an elevational end view of the device shown in Figure 3;

Figure 5 is a side view of the device illustrated in Figure 3;

Figure 6 is an enlarged sectional view illustrating a detail of construction and showing particularly the baffle utilized in association with the endless conveyor, and;

Figure 7 illustrates a portion of the shaft used in the invention.

Referring now in detail to the preferred form of the invention it is noted that a simplified device is illustrated for retaining, transporting and distributing grain, fertilizer and other appurtenances common to farm operations.

One of the prime features of the present in-

2

vention is its simplicity and adaptability to various and sundry purposes. By a very simple manipulation the device may be utilized for simply transporting grain or the like from one position or location to another locale. Then, by another extremely simple manipulation, the device may be transported to a distributing apparatus for spreading grain, fertilizer and other material. These operations may be performed from the rear portion of the device without constant maneuvering from one position to the other.

A suitable prime mover generally indicated at 10 is provided and may be conventional in nature. The usual power take-off 12, however, is associated with the rear portion of the conventional prime mover, whence power or torque is derived for actuation of the invention. A vehicle generally indicated at 14, is provided with a conventional draw bar 16 adapted to be attached to a conventional tractor draw bar through the medium of a suitable hitch illustrated at 18.

The make-up of the vehicle forms an important part of the present invention and is as follows: A pair of conventional wheels 20 are journaled on the chassis of the vehicle and a hopper 22 is associated therewith. Of course, end plates 24 and 26 respectively are associated with the said hopper and a convenient slider valve or gate is positioned in the end plate 26. The specific construction of this slider valve may be seen best in Figure 4 wherein a pair of channels 28 and 30 respectively serve the purpose of guide rails for the valve plate 32. A suitable handle 34 may be supplied on the said valve plate and the plate is reciprocable over an opening in the said plate 26.

A pair of stub shafts 35 and 36 respectively are provided in suitable brackets in the vehicle and suitable gears 38 and 40 are journaled on these shafts. Extending around these gears 38 and 40 is an endless conveyor.

The preferable form of the endless conveyor 45 is a simple chain 42 having a plurality of baffles 44 positioned thereon. This endless conveyor or chain extends through the end plate 26 and inspection of Figure 3 illustrates that the bracket for supporting the stub shaft 36 is also exterior of the hopper.

Of course, the baffles are utilized for the purpose of assisting in the removal of grain, fertilizer and the like from the hopper. Means for controllably actuating the endless conveyor is provided. This means may be seen as a friction

clutch illustrated particularly well in Figure 2. A plate 50 is splined on a shaft 52. This shaft extends beneath the hopper and connects with a segmental shaft 54 by means of a universal joint 56. A second segmental shaft 58 is also connected in this system and more specifically to the first mentioned segmental gear 54 by means of a second universal joint 60. Of course, the last mentioned segmental shaft 58 is adapted to be connected with the power take-off 12 of the prime mover 10.

A shaft 62 is journaled beneath the said hopper and is aligned with the said shaft 52. A sliding block 64 is positioned on the said shaft 62 by means of a suitable keyway and pin construction and has a plurality of lugs 66 extending therefrom. Slidably secured to the said lugs is a pressure plate 68, which is in turn rigidly secured to the slideable block 64. A plurality of springs or other suitable resilient biasing means 70 are supplied on the said lugs 66 and seat upon the pressure plate 68. These springs 70 also seat upon a clutch plate 72. The faces of the clutch plates 50 and 72 are suitably faced with facing 74, said facing being conducive of friction.

A bracket 76 is provided in the vehicle and has a yoke 78 pivotally secured thereto. An actuation arm 80 is in turn pivoted to the said yoke 78 and is preferably of pitman construction in order that a lever 82 may be associated therewith. The said yoke 78 is of course received in a suitable groove 84 in the said slideable block 64. By actuation of this lever 82, the yoke will of course urge the pressure plate which in turn biases the clutch plate 72 against the clutch plate 50 through the medium of the resilient springs 70.

A small housing 86 is secured to the said end plate 26 and has the terminal portion of the said shaft 62 journaled therein. A suitable bearing such as bronze or the like and indicated at 88 is supplied for this journaling construction. Received in the said housing 86 is a bevel gear 90 and this bevel gear is rigidly secured to the said shaft 62. Enmeshed with the said bevel gear 90 is a second bevel gear 92 which is in turn secured to the said shaft 36. Obviously, this construction permits the torque from the shaft 62 to be transmitted to the endless conveyor or chain 42.

For directing the grain and the like on the endless conveyor, the baffle 96 is secured to the lowermost portion of the said hopper 92 and is in juxtaposition relative to the baffles 44 of the endless chain 42. It will be noted further that in order to insure perfect centering during the actuation of the driving means, the shaft 62 is extended slightly (see Figure 2) for the purpose of being received in a suitably configured cut-out in the clutch plate 50. This of course leads the moving assembly in the clutch system to the substantially perfect alignment which is desirable for smooth operation of the clutch.

While there has been described and illustrated but a preferred form of the invention, it is apparent that variations may be made without departing from the spirit thereof.

Having described the invention, what is claimed as new is:

1. A trailer comprising, a vehicle, a hopper forming a part of said vehicle and having converging sides, conveyor means in said hopper, means for actuating said conveyor means adapted to be secured to a prime mover power take off for selectively controlling said actuation means, an outlet at the rear of said hopper, a slider valve

associated with said outlet, said conveyor means including gears journaled at the front and rear of said hopper and partially extending in said hopper having an endless chain therearound, baffles on said chain, said actuation means including a drive shaft disposed exteriorly of said hopper and alongside of one of the hopper walls, said actuation means including a friction clutch operatively connected with said drive shaft, and means carried by the rear part of the hopper for drivingly connecting said clutch and one of said gears.

2. A trailer comprising a vehicle, a chassis forming a part of said vehicle, a hopper disposed on said chassis and including converging side walls, a front and a back wall, an endless conveyor, a gear disposed on said chassis in front of said hopper front wall, a gear disposed at least partially within and behind the back wall of said hopper, both of said gears forming a part of said endless conveyor, a drive shaft disposed exteriorly of said hopper and alongside of one of said side walls, a clutch operatively connected with said shaft and means disposed at the rear of said hopper for operating said clutch, means operatively connected with said clutch and one of said gears to operate said endless conveyor, a sectional shaft disposed at the forward end of said shaft and connected with said shaft by means of a universal joint, said sectional shaft being adapted for operation by a prime mover component, and a gate disposed on the rear wall of said hopper to control an opening in said rear wall.

3. A trailer comprising a vehicle which includes a chassis, wheels carried by said chassis, a hopper disposed on said chassis and having a front, a rear and a pair of converging side walls, a shaft supported by and disposed above said chassis in side by side relationship with respect to one of said hopper side walls, a clutch mechanism secured to said chassis and disposed in side by side relationship to the same hopper side wall, said clutch being operatively connected with said shaft, a clutch control mechanism disposed at the rear of said hopper, said rear wall of the hopper having an opening therein with a gate operable to open and close said opening, an endless conveyor disposed in said hopper at the lower part thereof with means drivingly connecting the endless conveyor with the clutch mechanism, a sectional shaft having universal joints at both ends thereof, one of the universal joints being operatively connected with the forward end of said first mentioned shaft whereby upon operation of said sectional shaft through the other universal joint, said endless conveyor may be actuated, the operation of said endless conveyor being controlled by said clutch mechanism.
